WINDOW-CLIP.

1,101,832.

Specification of Letters Patent. Patented June 30, 1914.

Application filed October 24, 1912. Serial No. 727,533.

To all whom it may concern:

Be it known that we, DELAMAR C. BRIGGS and JOHN G. RUMNEY, citizens of the United States of America, residing at Detroit, in the county of Wayne and State of Michigan, have invented certain new and useful Improvements in Window-Clips, of which the following is a specification, reference being had therein to the accompanying drawings.

The invention relates to metallic window clips of that type employed for the securing of the glass pane in position in metallic window frames, and the invention consists in the peculiar construction as hereinafter set forth.

In the drawings:—Figure 1 is a cross section through a sash bar of a metallic window frame showing the clip applied thereto for securing the window pane in position; Fig. 2 is an elevation of the clip and bar as shown in Fig. 1; and Fig. 3 is a perspective view of the clip detached.

In the securing of window panes in position in metallic window sashes, various devices have been employed as a substitute for the points commonly employed with wooden sashes. It is essential that the means employed should hold the pane from accidental disengagement and it is equally important that it be easily engageable and disengageable with and from the window frame. Our improved construction fulfills these essential conditions, the construction being as follows:

A is one of the sash division bars of a metallic window sash which is formed with a shoulder B against which the pane rests and a flange C which extends between the adjacent panes.

Our improved clip consists of a bent resilient wire loop D having one end E laterally bent to engage an aperture F in the sash bar. The opposite leg G of the loop is of greater length and is provided with an oppositely laterally bent end portion H adapted to hook over the edge of the pane, while the leg G extends between said edge of the pane and the flange C. The relative arrangement

of the parts is shown in Fig. 2 and in as much as the hook E, which engages the aperture F, is intermediate the hook H and the main bend K of the loop, it is obvious that there will be no tendency for the clip once engaged, to spring out of position. 55

In placing the clips in position it is sometimes difficult for the workman to obtain a hold of the clip while engaging the hook E with the aperture F. We therefore preferably form the leg G with an inward bend I so therein which brings an intermediate portion J to the rear of the plane of the face of the glass over which the hook H is engaged. This enables the workman to obtain a finger hold of the leg G while he is placing 65 the clip in position.

What we claim as our invention is:

1. The combination with the bar of a metallic window sash, of a clip comprising a resilient wire loop having the legs thereof of different length and provided with oppositely laterally bent ends the bent end of the shorter leg being engageable with an aperture in said sash bar and the longer leg lying between the edge of the window pane 75 and said bar, and having its intermediate portion bent inward for a finger grip and its laterally bent end portion engaging the pane.

2. The combination with the angle bar of 80 a metallic window sash, of a pane securing clip comprising a loop of resilient wire having the legs thereof of different length and provided with oppositely laterally bent end portions, the bent end portions of the 85 shorter leg being engageable with an aperture in the flange of said sash bar and the longer leg having an inwardly bent intermediate portion forming a finger hold lying to the rear of the plane of the face of the 90 sash with portions upon opposite sides of this intermediate portion between the edge of the sash and said bar.

3. The combination with the bar of a metallic window sash, of a clip comprising a 95 resilient wire loop having the legs thereof provided with oppositely laterally bent ends, the bent end of one of the legs being

adapted to engage an aperture in the sash bar and the other leg being adapted to lie between the edge of the window pane and the sash bar, and having its intermediate portion bent inward for a finger grip and its laterally bent end portion being adapted to engage the pane.

In testimony whereof we affix our signatures in presence of two witnesses.

DELAMAR C. BRIGGS.
